(57) CLAIM

The ornamental design for a gaming device having a symbol display, as shown and described.

DESCRIPTION

This application is related to the following commonly-owned co-pending patent application: "Gaming Device Having Symbol Displays," Ser. No. 29/225,744.

The sole FIGURE is a front perspective view of the symbol display for a gaming device of our new design, that fragmentary portion of the gaming device shown in phantom is not part of the design sought to be patented and is provided for environmental purposes only.
